Primary Examiner — Melanie H Tung*Assistant Examiner* — Fitzgerald Butac(74) Attorney, Agent, or Firm — Snell & Wilmer L.L.P.(57) CLAIM

The ornamental design for a bottle, as shown and described.

DESCRIPTION

FIG. 1 is a front perspective view of a bottle showing our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines shown in FIGS. 1 through 7 illustrate portions of the bottle which form no part of the claimed design.

1 Claim, 7 Drawing Sheets(56)
